UNITED STATES PATENT OFFICE.

ARTHUR L. RUSSELL, OF HYDE PARK, MASSACHUSETTS, ASSIGNOR TO UNITED SHOE MACHINERY COMPANY, OF PATERSON, NEW JERSEY, A CORPORATION OF NEW JERSEY,

MACHINE FOR USE IN THE MANUFACTURE OF BOOTS AND SHOES.

1,033,945.

Specification of Letters Patent. Patented July 30, 1912.

Application filed July 24, 1907. Serial No. 385,298.

To all whom it may concern:

Be it known that I, ARTHUR L. RUSSELL, a citizen of the United States, residing at Hyde Park, in the county of Norfolk and 5 Commonwealth of Massachusetts, have invented certain Improvements in Machines for Use in the Manufacture of Boots and Shoes, of which the following description, 10 in connection with the accompanying drawings, is a specification, like reference characters on the drawings indicating like parts in the several figures.

This invention relates to machines for working uppers over lasts and particularly 15 to mechanism in such machines for securing the upper in overworked position by means of a binder of continuous material.

It has been the practice for the laster, 20 after the forward portion of an upper has been worked into lasted position upon the shoe bottom, to drive a tack at one side of the shoe to which was anchored an end portion of a tape, wire or other strand of continuous material adapted to serve as a 25 binder. The strand was then drawn about the toe portion of the shoe into such relation to the overworked upper as to bind the upper against the lip or shoulder of the innersole and then secured to another anchor tack after which the main portion of 30 the strand was cut from the binder. This procedure consumes a considerable length of time of a skilled workman and the binder is not always drawn into position to hold 35 the upper securely.

An object of the present invention is to provide novel means by the use of which an upper may be fastened by a binder more quickly and in a more uniform manner 40 than has heretofore been possible.

To this end a feature of the invention consists in means for forcing a binder into position to hold an upper and means for securing the binder. Preferably the binder 45 will be forced into holding position automatically and preferably it will be secured automatically, but it is also a feature of this invention to fasten a binder automatically whether or not the binder is forced into 50 binding position by automatic or other mechanism or manually. As herein shown, means is provided for supporting a binder

of continuous material at opposite sides of a shoe and for moving the binder and the shoe relatively to force the binder into holding position, together with means for fastening the binder, as, for example, by means of tacks or similar devices. Preferably the supporting means is movable relatively to the last to put the binder into suitable position upon the shoe and also to draw the binder tightly about the shoe.

A further feature of the invention consists in tack driving mechanism constructed and arranged when actuated to move automatically into suitable relation to the binder supporting means to drive a tack into position to fasten the binder. In the embodiment of the invention shown the binder supports occupy different positions at different times according to the shape and size of the shoe, and tack driving mechanisms are located at opposite sides of the shoe and when actuated adjust themselves automatically to the location of the binder supports and into position to insert tacks in predetermined relation to the binder for use in securing both ends of the binder.

A further feature of the invention consists in operatively connecting a binder support and a tacking mechanism so that, preferably upon a single actuation, they will position a binder in holding relation to the shoe and drive a tack in position for securing the binder. In the preferred embodiment of this feature of the invention, supporters and tacking mechanisms are operatively connected to a common actuator by which the supporters are caused to position the binder upon the shoe and tighten it about the end portion of the shoe, and the tacking mechanisms are moved into proper positions to drive a tack for securing the binder at opposite ends and are actuated to insert the tacks.

A further feature of the invention consists in arranging a binder support and a tacking mechanism relatively so that during the movement of the latter into tack driving position the binder is automatically drawn or tightened into holding engagement with the shoe. As shown the support is movably mounted on a carrier by which the binder is positioned upon the shoe.

bottom and the supporter is actuated to tighten the binder by the movement of the tacking mechanism into driving position. The supporter is shown as comprising a lever having one arm to which the binder is connected and a second arm that is engaged by the tacking mechanism for rocking the lever to draw the binder tightly about the shoe. A yielding element will preferably be provided by which excessive straining of the binder will be prevented.

Another feature of the invention consists in providing means for cutting the binder from a strand of binding material. Preferably this is done automatically while the shoe is in the machine and as shown the binder is severed from the strand after the tack has been driven and during the return of the parts to their normal position.

The mechanism herein shown is adapted for using a binder of tape and a feature of the invention consists in provision for relatively positioning the binder and the tacking mechanism for a tack to be driven in predetermined lateral relation to the binder, preferably through it if it is a tape, to secure the binder in holding position.

The tack may be a single pointed tack or a double pronged tack or staple. In the latter case, the staple may be positioned with relation to the tape to have one or both prongs pass through it or it may be arranged to straddle the tape.

It is also within this invention to use a binder of wire or similar material and fasten it by a staple driven across it or by a tack about the stem of which the wire is bent.

A mechanism for drawing a wire binder into holding position about a shoe and automatically fastening it by bending it about a tack is shown and specifically claimed in another application Serial No. 387,613, filed August 8, 1907.

The embodiment of the invention herein illustrated comprises means for pulling-over a shoe upper and means for lasting the forward portion of the shoe, and features of the invention include combinations with means for working an upper over a last, whether automatically or otherwise, of my improvements in means for securing the upper by a binder.

These and other features of the invention including certain details of construction and combination of parts will be explained in the following description and pointed out in the claims.

Figure 1 is a side elevation of a machine equipped with the present invention. Fig. 2 is a perspective view showing certain of the mechanisms which directly engage the shoe in working the upper over the last, together with the binder supporters. The position of the parts here shown is that which

they may occupy when the upper has been pulled-over and forced into lasted position about the forward portion of the last and a section of continuous material after having been passed about the toe end of the shoe has been carried by the binder supporters into holding position over the shoe bottom ready to be tightened for binding the upper into the angle of union between the feather edge and lip or shoulder of the innersole. Fig. 3 is a perspective view of the binder supporter and its carrier on a larger scale. Fig. 4 is a section on approximately the plane of the line 2-2 of Fig. 1. Fig. 5 is a section on approximately the plane of the line 3-3 of Fig. 1. Fig. 6 is a plan view showing the relative position of the parts after the binder has been passed around the forward portion of the shoe, and gripped by the clamps. Fig. 7 is a perspective view of a shoe as it comes from the machine. Figs. 8, 9, and 10 are detail views showing different ways of fastening a binder with single and double pointed tacks. Fig. 11 is a view of the cutters in open position.

The invention is herein shown, for the purpose of explanation, as applied to a machine for performing the combined operation of pulling-over and lasting shoes. It is however adapted to be used in combination with any machine for working an upper over a last or may be employed independently of the operation of such machines.

The machine shown comprises a sole rest 2 against which the shoe is presented in inverted position as indicated in Fig. 1. Grippers 6 are arranged at opposite sides of the shoe and at the toe and are connected pivotally to levers 8 by which the gripper jaws are closed and then uplifted for pulling the upper. The levers are pivoted at 10 and each yieldingly connected, as at 12 in Fig. 1, to a slide which is actuated by a cam on the main shaft 14. The front ends of the levers are formed as handles by which any gripper may be manually moved up or down for adjusting the upper. The side grippers may also be moved forwardly or backwardly by a connection through a rack bar 15 with a shaft 16 having a handle 18. The grippers are held separated a suitable distance while the upper is being pulled by a slide 17, see Fig. 1, having inclined sides, as shown in Fig. 5. A stud on the rear end of the slide is engaged by a stud on another slide 19 which is controlled by a toothed shaft 20 and a lever 21 which engages a cam 22 on the main shaft 14. Springs 23 press the grippers inwardly to carry the upper over the last bottom when the slides are retracted. These parts of the machine and other parts of the pulling-over mechanism which it does not appear to be necessary to describe for the purpose of explaining this invention may be substantially as in United

States Letters Patent No. 663,777, granted on the application of Ronald F. McFeely, to which reference may be had for a complete understanding of the machine and its operations.

After the upper has been pulled into conformity with the general contour of the last and adjusted into the desired relation to the last, it is worked into lasted position by a 10 mechanism comprising wiper plates 24, connected directly at 25 and indirectly through links 26, and bar 27 with a rack slide 28, which is engaged by a pinion on the shaft 29, that has a hand lever 30 by which the 15 plates may be actuated for wiping the upper into lasted position over the innersole. The plates are preferably mounted in a vertically movable carrier 32 connected by a rack and pinion as indicated in Fig. 1 with a 20 hand lever 34 by which the plates may be moved up and down. The plates also preferably have their acting edges formed and arranged to force the upper into the angle of union between the lip 35 and the feather 25 edge 36 of the innersole. At the sides of the shoe the upper is worked into lasted position by pressers 40, which are mounted on carriers 42 that are shown in Fig. 4 as angle levers connected to a slide 43 having a stud 30 44 that stands in a groove of a cam on the main shaft. The carriers 42 also have cushions 45 for sustaining the last against the impact of the tack drivers.

Binder supporting means is arranged at 35 opposite sides of the shoe for holding the ends of a section of binding material passing about the forward portion of the shoe as shown in Figs. 2, 4 and 6. Each binder support comprises a clamp formed on the 40 arm of an angle lever made of the two members 50, 51. These members are pivoted at 52 to the carrier and have adjacent arms which are yieldingly connected by a rod 54 encircled by a spring 55. The arrangement 45 is such that pressure on the outer side of the member 51 will be transmitted yieldingly through the spring to rock the member 50 and the clamp rearwardly or to the left in Fig. 3. The clamp comprises a rigid 50 jaw 60 the lower gripping face of which is downwardly and forwardly inclined, and a movable member in the form of a loose roll 62 which is guided between walls 63 and 64 and is pressed by a spring 65 forwardly to 55 wedge the binder against the rigid jaw. A finger lever 66 pivoted to the member 50 provides means for moving the roll rearwardly for opening the clamp to insert the binder or permit it to be advanced through 60 the clamp.

A fixed shear blade 70 is attached to the presser 40 and a sliding blade 72 has a pin and slot connection with the presser at 74 and at its outer end is connected to the member 51 of the supporter to be actuated by

said member in one direction. A spring-pressed plunger 75 engages the member 51 for actuating the shear blade 72 to sever the binder, and the plunger holds the parts normally in the position shown in Figs. 2 and 3 70 with the clamp forward and the movable shear blade covering the fixed blade and protecting the binder from contact with the cutting edges of the blades. The blades hold the tape above its straight course from the clamp so that when the shears are opened the binder, then held under tension will drop between the blades into position to be cut off.

The presser 40 is constructed to guide the 80 binder and to this end it is formed with a groove 76 having the high inner wall 78 against which the binder will be positioned as it extends from the clamp forwardly about the toe portion of the shoe. The 85 lower wall of the guideway is tapered to present a thin front edge adjacent to the point at which the binder is to be secured. The binder may be provided in pieces of suitable length for individual shoes, but 90 preferably it will be taken from a reel 70, the end portion being passed about the shoe and the binder severed from the strand after it has been fastened in holding position. The shears are spaced far enough from the 95 clamp to leave an end of the strand in position for the operator to take hold of in drawing out the strand for the next shoe.

The mechanism for fastening the binder comprises tack driving devices shown in 100 Figs. 4 and 5. These devices at each side of the shoe include duplicate tack blocks 80 and corresponding drivers 82, the tacks being supplied through tubes from a feeding mechanism in the upper portion of the machine while the drivers are actuated by 105 levers 83. The tacking mechanisms are movable from a separated position shown in Fig. 6, where they are out of the way during the pulling-over, lasting and binder 110 placing operations, into the positions over the shoe bottom shown in Figs. 4 and 5. This movement is effected yieldingly through connections with the slide 19 previously referred to. These connections may 115 be the same as those shown for the purpose in the Letters Patent above mentioned, as may also be the means for tripping the drivers at the proper time to cause them to insert the tacks.

Each tacking mechanism is provided with an abutment 84 which is formed and arranged to engage the member 51 of the binder supporter during its movement into driving position. By this engagement each 125 supporter is rocked to pull upon the end of the binder engaged by its clamp and draw the binder snugly into holding engagement with the upper for binding the upper in lasted position. The spring connection be- 130

tween the two members 50 and 51 permits the member 51 to have its full stroke for actuating the shear blade 72, while preventing excessive strain upon the binder. The tacking mechanism is stopped in its inward, 5 yieldingly effected movement by engagement of the abutment 84 with the carrier upon which the binder supporter and the presser 40 are mounted, or more exactly by engagement with the member 51 that lies between said abutment and the carrier. By this arrangement the tacking mechanism is positioned in predetermined lateral relation to the binder. As herein shown the binder 10 guide and the holder for the front tack *t* are so formed and arranged relatively that the tack is directly over the binder when the mechanism is stopped and is inserted through the binder which is shown as a piece of tape or similar material through 15 which a tack can be driven. Instead of a single pointed tack a double pointed tack or staple may be employed and the holder for it may then be so arranged that both points will be driven through the binder or so that the staple will be driven across or straddling the binder this being determined by the angular position in which the tack holder is formed to present the tack 20 to the binder. If the binder is straddled by the tack the binder may be a wire or the like. If a wire binder is to be used with a single pointed tack then the tack may be driven adjacent to the wire and the end of 25 the binder bent around the shank of the tack. Such a construction is within the broad scope of this invention and a mechanism for driving tacks and automatically bending the ends of a binder about the stem 30 of the tack, as shown in Fig. 10, is illustrated and claimed specifically in said other application.

In the use of the invention as embodied in the illustrated construction, a shoe comprising 35 an innersole and upper materials assembled on a last is presented in the position shown in Fig. 1 with the innersole against the sole rest 2 and the heel end against the heel rest 4, and the edge portion of the upper between the jaws of the grippers. The machine is started by mechanism which may be the same as that shown in United States Letters Patent No. 791,986, and is arranged to stop the machine automatically 45 at predetermined periods in its cycle of operation. During the first actuation of the machine the grippers seize and pull the upper into conformity with the general shape of the last. During the following 50 rest in the machine's operation the workman adjusts the upper by moving the grippers manually through the handles 18 and the levers 8 as may be necessary to position it properly upon the last. The machine may 55 then be restarted whereupon the grippers

will carry the upper over the last bottom, after which the machine will preferably again come to rest. The workman will then use the lasting plates to work the upper of the toe portion of the shoe into lasted position, as shown in Fig. 6. The clamp nearest the reel will then be opened by the finger lever 66 to permit the strand of binding material to be drawn through it and passed about the forward portion of the shoe, as in Fig. 6, the lasting plates being raised slightly by the hand lever 34 to permit the binder to enter the seat formed for it by the lasting plates in the upper adjacent to the angle of union between the lip and feather edge of the innersole. The free end of the binder will be drawn into the clamp on the second side of the shoe which will be closed by its spring 65 when the binder has been positioned without slack about the shoe. The machine may then be started again and the carriers will be moved inwardly from the position shown in Fig. 6 to the position shown in Fig. 2, carrying the binder into position over the shoe bottom at the sides of the shoe. Preferably, the carrier levers in swinging about their fulcrums toward the shoe will retract the carriers more or less so that the binder will be tightened during this movement. The levers are yieldingly actuated so that the pressers position themselves relatively according to the width of the shoe in the machine and are stopped by the cushions 45 in uniform position with relation to the edge of the shoe. 95 The tacking mechanisms follow the pressers inwardly and as they approach tacking position the abutments 84 strike the members 51 of the binder supporters and move them inwardly toward the positions shown in Fig. 4. Their movements are yieldingly transmitted to the members 50 and the clamps by which the binder is simultaneously pulled at both ends to draw it into binding relation to the upper. This straining of the binder is effected by a substantially equal pull upon the opposite ends of the binder so that the binder is not displaced endwise about the last and the upper 100 at each side of the shoe is held with the same security. In the movement of the member 51, the shear blade 72 is forced inwardly away from the fixed blade, thus opening a space between the two blades into which the binder drops or is pulled as the tension is applied to it. Preferably the upper face of the blade is above the normal course of the binder so that the clamp pulls the binder down into the shears as soon as they are opened. As the tacking mechanisms move inwardly they preferably engage tripping devices 85 on the side grippers which permit those grippers to open and release the upper that it may lie closely against the innersole where the tacks are to 115 120 125 130

be driven. These preliminary operations having been accomplished and the holder for each front tack being in position to insert its tack in desired lateral relation to the binder, the drivers are tripped and the tacks driven on both sides of the shoe at the same time. Preferably, the tacks fasten the binder by passing through it or over it as shown in Figs. 8 and 9. If the binder is a wire the tack may be driven beside it in position for the wire to be bent about it as shown in Fig. 10. The lasting plates may remain in a position resting loosely over the binder, as shown in Fig. 2, where they will hold the binder from riding up over the upper as it is drawn into holding position, and the toe grippers may retain their engagement with the upper during the binding operation to hold it in an upright position above the binder at the end of the toe, thus also tending to prevent the binder from rising out of its binding position. After the tacks are driven the tacking mechanisms back off and the spring-pressed plunger actuates the member 51 to close the shears and cut the binder between the securing tacks and the clamps, leaving the end portion of the strand in the right hand clamp where it may be conveniently seized by the workman for use on the next shoe. Following the tacking mechanisms the other automatically actuated parts resume their starting positions, the two grippers opening to release the upper. The toe grippers may be opened at any time by actuating their tripping device 85.

Having explained the nature of this invention and described one construction in which it may be embodied, I claim as new and desire to secure by Letters Patent of the United States:—

1. In a machine of the class described, mechanism for applying a binder to hold an upper in overworked position about the forward portion of a shoe, comprising binder supporting means arranged to grip the binder at opposite ends and movable inwardly over the shoe bottom from opposite sides of the shoe, and means for relatively actuating the supporting means and the last for automatically drawing the binder about the upper.

2. In a machine of the class described, mechanism for applying a binder to hold an upper in overworked position about the forward portion of a shoe, comprising binder supporting means arranged to grip the binder at opposite ends, means for relatively actuating the supporting means and the last for automatically drawing the binder about the upper, and automatically operated means for fastening the binder.

3. In a machine of the class described, mechanism for applying a binder to hold an upper in overworked position about the for-

ward portion of a shoe, comprising binder supporting means located at opposite sides of the shoe and movable inwardly over the shoe bottom, means for tightening the binder about the upper, and means for securing the binder in holding position. 70

4. In a machine of the class described, mechanism for applying a binder to hold an upper in overworked position about the forward portion of a shoe, comprising binder supporting means, and automatically operating means for securing the binder in holding position. 75

5. In a machine of the class described, mechanism for applying a binder to hold an upper in overworked position about the forward portion of a shoe, comprising binder supporting means located at opposite sides of the shoe, and means for automatically moving the supports inwardly over the shoe, 80 of means for actuating the supports to tighten the binder about the upper, and means for securing the binder in position to hold the upper. 85

6. In a machine of the class described, mechanism for securing an upper in overworked position about the toe of a shoe, comprising means for supporting a binder, automatically operating means for forcing the binder into holding position, and automatically operating means for securing the binder at its opposite ends. 95

7. In a machine of the class described, mechanism for securing an upper in overworked position about the toe of a last, comprising means for supporting a section of continuous binding material extending about the forward portion of the shoe, and automatically operating mechanism for tightening the binding material about the 100 shoe, securing it to the shoe, and severing the section from the strand of material. 105

8. In a machine of the class described, the combination with means for working an upper into lasted position about the toe end of a last, of means for securing the upper, comprising devices for holding the opposite ends of a binder, and means for automatically actuating the holding devices to draw the binder into holding relation to the 110 upper independently of the actuation of the overworking means. 115

9. In a machine of the class described, the combination with means for working an upper into lasted position about the toe end of a last, of means for securing the upper, comprising devices for holding the opposite ends of a binder, means for actuating the holding devices and the last relatively to draw the binder into holding relation to the upper independently of the operation of the overworking means, and means for fastening the binder in holding position. 120 125

10. In a machine of the class described, the combination with means for working an 130

- upper into lasted position about the toe end of a last, of means for securing the upper, comprising devices for holding a section of continuous material adapted to form a binder, means for actuating the holding devices to draw the binder into holding relation to the upper, means for securing the binder, and means for severing the binder from the strand of continuous material.
11. In a machine of the class described, the combination with means for gripping an upper and pulling it over a last, and mechanism for applying a binder to hold the upper about the end of the shoe, comprising means for gripping and holding the ends of the binder at opposite sides of the last, said gripping means being movable inwardly and backwardly to carry the binder over the shoe bottom for tightening the binder and drawing its ends into position to be fastened, and means for fastening the binder.
12. In a machine of the class described, the combination with means for pulling an upper over a last, supports for receiving the binder, means for moving said supports into position over the shoe bottom, means for tightening the binder about the toe of the shoe, means for fastening the binder in holding position, and means for severing the binder from the strand.
13. In a machine of the class described, the combination with means for pulling an upper over a last, means for adjusting the upper about the last, means for forcing the upper into lasted position, holders for a binder of continuous material, means for actuating the holders to position the binder about the end of the shoe, and means for fastening the binder.
14. In a machine of the class described, the combination with means for working an upper over a last, of holders arranged at opposite sides of the last for a binder, drivers movable over the shoe bottom, and means for automatically positioning the holders and the drivers relatively whereby the binder is located in the path of movement of the drivers.
15. In a machine of the class described, the combination with means for working an upper over a last, of holders independent of said means and arranged at opposite sides of the last for a binder, tack driving devices arranged to insert tacks to fasten the binder substantially at the holding points, and means for actuating the tack driving devices.
16. In a machine of the class described, the combination with means for working an upper over a last, of means operated independently of the overworking means for supporting an end of a binder that extends from one side of the shoe about the toe of the shoe to the other side, tack inserting mechanism, means also supported and op- erated independently of the overworking means for actuating the inserting mechanism into position for driving a tack to secure the said end of the binder to the shoe, and means for relatively positioning the inserting mechanism and the binder for the latter to receive the tack.
17. In a machine of the class described, the combination with means for working an upper over a last, of means for supporting over the shoe bottom at opposite sides of the last the ends of a binder which extends about the toe of the shoe, tack inserting mechanisms, means for actuating the tack inserting mechanisms over the shoe bottom, and stops for arresting the inserting mechanism in position to drive tacks through the binder.
18. In a machine of the class described, the combination with means for working an upper over a last, of means for supporting an end of a binder that extends from one side of the shoe about the toe of the shoe to the other side, tack inserting mechanism, means for actuating the inserting mechanism into position for driving a tack to secure said end of the binder to the shoe, and means for automatically tightening the binder about the shoe.
19. In a machine of the class described, the combination with means for working an upper over a last, of means for supporting an end of a binder that extends from one side of the shoe about the toe of the shoe to the other side, tack inserting mechanism, means for actuating the inserting mechanism into position for driving a tack to secure the said end of the binder to the shoe, means actuated by the inserting mechanism for automatically tightening the binder about the shoe, and means for relatively positioning the inserting mechanism and the binder for the latter to receive the tack.
20. In a machine of the class described, the combination with means for working an upper over a last, of means for supporting the end of a section of continuous material that extends from one side of the shoe about the toe of the shoe to the other side, tack inserting mechanism, means for actuating the inserting mechanism into position for driving a tack to secure the end of the section to the shoe, and operatively connected means for severing the section from a strand of continuous material.
21. In a machine of the class described, the combination with means for working an upper over a last, of devices for holding the ends of a binder over the shoe bottom at opposite sides of the last, tack inserting mechanisms, means for actuating said mechanisms into inserting positions, and means actuated by the movement of said mechanisms for operating the holders to tighten the binder about the shoe, and means for

actuating said mechanisms to insert tacks for holding the binder at its opposite ends.

22. In a machine of the class described, the combination with means for working an upper over a last, of means for holding at opposite sides of the shoe a section of continuous material extending about the toe of the shoe and adapted to bind the upper in overworked position, tack inserting mechanisms movable into position to drive tacks for securing the binder in holding position, means actuated by said mechanisms for drawing the binder into holding position, and automatically operated means for severing the binder from the strand of continuous material while the shoe remains in the binder fastening position.

23. In a machine of the class described, the combination with means for working an upper over a last, of means for holding at opposite sides of the shoe a section of continuous material extending about the toe of the shoe and adapted to bind the upper in overworked position, tack inserting mechanisms movable into position to drive tacks for securing the binder in holding position, means actuated by said mechanisms for drawing the binder into holding position, and a cutter constructed and arranged to sever the binder from the strand of continuous material automatically on the reverse movement of the inserting mechanisms.

24. In a machine of the class described, the combination with means for working an upper over the toe portion of a last, of additional means operating automatically for drawing a binder into position to hold the upper and to maintain the binder under tension to permit it to be fastened, and means for severing the binder from a strand of binder material.

25. In a machine of the class described, the combination with automatically operating mechanism for working an upper over a last, of means for tightening a binder about the forward portion of the shoe in position to hold the upper, and means for fastening the binder.

26. In a machine of the class described, the combination with mechanism for working an upper over a last, of means for automatically tightening a binder about the forward portion of the shoe in position to hold the upper, and means for fastening the binder.

27. In a machine of the class described, the combination with mechanism for working an upper over a last, of means for tightening a binder about the forward portion of the shoe in position to hold the upper, and means for automatically fastening the binder.

28. In a machine of the class described, automatically operating mechanisms for

working an upper over a last, drawing a binder into position to hold the upper, and fastening the binder.

29. In a machine of the class described, the combination with mechanism for working an upper over a last, of means for tightening the end portion of a strand forming a binder about the forward portion of a shoe into position to hold the upper, means for fastening the binder, and means for automatically severing the binder from the strand.

30. In a machine of the class described, the combination with mechanism for working an upper over a last, of clamps and means for moving the clamps to tighten a binder about the forward portion of a shoe, means for driving tacks to fasten the binder, and means for severing the binder between the clamps and the tacks.

31. In a machine of the class described, the combination with a presser movable over the shoe bottom to press the upper material into position to be secured, said presser being constructed and arranged to guide a binder in predetermined position, of means supported independently of the presser for inserting a tack into position to secure the binder to the shoe.

32. In a machine of the class described, the combination with a presser movable over the shoe bottom to press the upper material into position to be secured and provided with a recess for guiding a binder, of a tack carrier and a driver movable relatively to the presser into position for inserting a tack in predetermined relation to the binder in said recess.

33. In a mechanism of the class described, means for gripping and firmly holding the opposite ends of a length of binding material adapted to extend about the forward portion of a shoe and pulling the two ends simultaneously to tighten the binder in holding position, combined with actuating means to carry the binder end holders and pullers inwardly from a position outside the shoe edge to a position inside the shoe edge for the binder ends to be fastened, and means for fastening the binder while it is under tension.

34. In a mechanism of the class described, means movable backwardly and also inwardly over opposite sides of the shoe bottom for pulling simultaneously upon opposite ends of a binder extending about the forward portion of a shoe to hold the upper in overworked position, and mechanism for driving tacks simultaneously through the opposite ends of the binder.

35. In a mechanism of the class described, automatically operated means movable inwardly over opposite sides of the shoe bottom for pulling a binder that extends about the forward portion of a shoe into position

- to hold the upper in overworked position, and means for simultaneously fastening the binder at opposite ends while it is held under tension.
- 5 36. In a machine of the class described, means for pulling over a shoe, said means having provision for adjusting the shoe upper about the last, and means for lasting the shoe, automatically operated means 10 for thereafter drawing a binder into position to hold the upper in overworked relation to the last and fastening the binder.
37. In a machine of the class described, means for pulling over a shoe, separately 15 operated means for drawing a binder into position to secure the upper, and means supported independently of the binder drawing means for fastening the binder.
38. In a machine of the class described, 20 means for working an upper into lasted position over the edge of the last, other means supported and operated independently of the overworking means and having a movement to carry the binder ends inwardly over the shoe bottom for drawing a binder into 25 position to hold the overworked upper, and means for fastening the binder.
39. In a machine of the class described, 30 means for working an upper into lasted position, and automatically operating means for drawing a binder into position to hold the overworked upper and fastening the binder, and means for severing the binder from the strand of binder material adapted 35 to operate while the shoe remains in position for the binder to be fastened.
40. In a machine of the class described, the combination with lasting plates for 40 working an upper into lasted position about the forward portion of a last, of means capable of operation independently of the lasting plates for drawing a binder into position to hold the overworked upper, and means for fastening the binder.
- 45 41. In a machine of the class described, the combination with lasting plates for 50 working an upper into lasted position about the forward portion of a last, of means which is movable inwardly over the last bottom and is adapted for gripping the opposite ends of a binder extended about the forward portion of the overworked upper, said means being constructed and arranged to prevent substantial relative movement of 55 the binder in the gripping means, and automatically operating means for relatively actuating the last and the gripping means to apply tension to the binder and hold it under tension while it is being fastened.
- 60 42. In a mechanism of the class described, 60 binder supporting means comprising levers having clamps for engaging a binder, and means for actuating the levers to apply tension to the binder.
- 65 43. In a mechanism of the class described, 65 binder supporting means provided with clamps comprising a fixed jaw, a guideway inclined toward the gripping face of the fixed jaw, a roll mounted in the guideway, and means for wedging the roll toward the 70 fixed jaw.
44. In a mechanism of the class described, 75 binder supporting means provided with clamps comprising a fixed jaw, a guideway inclined toward the gripping face of the fixed jaw, a roll mounted in the guideway, a spring for holding the roll normally in gripping relation to the fixed jaw, and a device for moving the roll away from the fixed jaw.
45. In a mechanism of the class described, 80 a binder support comprising angle levers pivoted on the same fulcrum, yielding means for holding adjacent arms of the levers together, a binder clamp mounted on the second arm of one lever, and means for rocking the second arm of the other lever whereby movement is yieldingly transmitted to the clamp.
46. In a mechanism of the class described, 85 a support for one end of a binder which extends about the forward portion of a last, mechanism movable toward and from position for inserting a tack to fasten the binder, guiding means located adjacent to the tacking point for positioning the binder and means for stepping the tacking mechanism in operative relation to the binder.
47. In a mechanism of the class described, 90 binder supporting means, mechanism for driving a tack to fasten the binder, and mechanism for cutting the binder strand between the tack and the support.
48. In a mechanism of the class described, 95 binder supporting means, mechanism for driving a tack to fasten the binder, and automatically operating mechanism for cutting the binder strand between the tack and the support.
49. In a mechanism of the class described, 100 binder supporting means, mechanism for driving a tack to fasten the binder, and normally closed shears in the course of the binder from the support to the operative 105 position of the tacking mechanism, means for opening the shears, means for applying tension to the binder strand and pulling it into the shears, and means for actuating the shears to sever the strand.
50. In a machine of the class described, 110 means for tightening a binder that extends about the toe portion of a shoe, means for holding the binder from rising out of binding position while it is being tightened, and means for fastening the binder.
51. In a machine of the class described, 115 means for tightening a binder that extends about the toe portion of a shoe, means for holding the upper at the end of the toe in upright position while the binder is tight- 120
- 125
- 130

ened, means for fastening the binder, and means for severing the binder from a strand of binder material.

52. In a machine of the class described, binder supports and tacking mechanisms, combined with means for relatively actuating said parts to position the binder about the shoe and to fasten the binder.

53. A machine of the class described having, in combination, means for applying a binder of continuous material to hold an upper in lasted position, and means operating automatically to sever the binder from a strand of binding material.

54. A machine of the class described having, in combination, means for applying a binder of continuous material to hold an upper in lasted position, means operating automatically to fasten the binder, and means for severing the binder from a strand of binding material.

55. A machine of the class described having, in combination, mechanism for working an upper into lasted position about the end portion of a last and fastening it by a binder of continuous material, and means operating automatically for severing the binder from a strand of binding material.

56. A machine of the class described having, in combination, means for applying a binder of continuous material to hold an upper in lasted position, means for fastening the binder, and means associated with the fastening means for severing the binder from a strand of binding material.

57. A machine of the class described having, in combination, means for applying a binder of continuous material to hold an upper in lasted position, means for fastening the binder, means arranged adjacent to the tightening means and to be operated automatically in time relation with the fastening means to sever the binder from a strand of the binding material.

58. A machine of the class described having, in combination, means for applying a binder to secure an upper in lasted position about the end portion of a last, and means for severing the binder from a strand of binding material while the shoe remains in binder-applying position.

59. A machine of the class described having, in combination, mechanism for working an upper over the forward portion of a last, separate means operating automatically to tighten a binder of continuous material about said portion of the shoe as a whole to hold the upper in lasted position and means for fastening the binder.

60. A machine of the class described having, in combination, mechanism for working an upper over the forward portion of a last, separate means operating automatically to tighten a binder of continuous material about said portion of the shoe as a whole to

hold the upper in lasted position, and means for cutting the binder from a strand of binder material.

61. A machine of the class described having, in combination, mechanism for working an upper over the forward portion of a last, devices located at opposite sides of the shoe and movable relatively to one another transversely of the shoe, said devices being adapted for gripping the two ends of a binder of continuous material extended about the toe of the shoe, and means for actuating said devices to tighten the binder, carry it inwardly over the last bottom, and hold it under tension to permit it to be fastened.

62. In a machine of the class described, mechanism for securing an upper in over-worked position about the toe of a last, comprising grippers for locking the two ends of a binder at opposite sides of the last, an automatically operating means for forcing the binder into position to hold the upper.

63. A machine of the class described having, in combination, means for pulling an upper over a last, supports for receiving a binder, means for moving said supports into position over the shoe bottom, and means for additionally actuating said supports to tighten the binder about the toe end of the shoe.

64. A machine of the class described having, in combination, means for gripping an end portion of a binder and carrying it laterally over a last and drawing it backwardly to tighten it into position to hold an upper about the toe portion of the last, and automatically driven means for fastening the binder.

65. A machine of the class described having, in combination, means for carrying an end portion of a binder laterally over a last and drawing it backwardly to tighten it into position to hold an upper about the toe portion of the last and holding the binder under tension to permit it to be fastened, and means for severing the binder from a strand of binder material.

66. A machine of the class described having, in combination, means for gripping an end portion of a binder and carrying it laterally over a last and drawing it backwardly to tighten it into position to hold an upper about the toe portion of the last, and automatically driven means for fastening the other end of the binder.

67. A machine of the class described having, in combination, means for pulling-over a shoe, means for lasting the forward portion of the shoe, and other means for binding the lasted portion of the shoe.

68. A machine of the class described having, in combination, means for pulling-over a shoe, means for lasting the forward portion of the shoe, other means for tightening

- a binder about the lasted end of the shoe, and means for driving tacks to fasten the binder.
69. A machine of the class described having, in combination, means for pulling-over a shoe, means for lasting the forward portion of the shoe, other means for binding the lasted portion of the shoe, and means for cutting the binder from a strand of binder material.
70. A machine of the class described having, in combination, relatively movable lasting plates, means for operating them to wipe an upper over an end portion of a last, and other means arranged to be actuated automatically to bind the upper in lasted position and mechanism to fasten the binder.
71. A machine of the class described having, in combination, lasting plates, means for operating them to wipe an upper over an end portion of a last, other means for tightening a binder about the lasted end of the shoe, and means for driving tacks to fasten the binder.
72. A machine of the class described having, in combination, lasting plates, means for operating them to wipe an upper over an end portion of a last, other means for binding the upper in lasted position, including automatic means for fastening the binder, and means for severing the binder from a strand of binding material.
73. A machine of the class described having, in combination, lasting plates, means for operating them to wipe an upper over an end portion of a last, means for placing a binder, means for fastening the binder, and means for severing the binder from a strand of binding material.
74. A machine of the class described having, in combination, means for working an upper over a last, and means for binding the upper including a binder support movable transversely of the shoe in placing the binder and having an independent movement lengthwise of the shoe to tighten the binder.
75. A machine of the class described having, in combination, means for working an upper over a last, and means for binding the upper including a binder support movable first transversely of the shoe to place the binder and then lengthwise of the shoe to tighten the binder.
76. A machine of the class described having, in combination, means for working an upper over a last, a binder support, mechanism for actuating it relatively to the over-working means to place the binder tightly about the last, and means for fastening the binder.
77. A machine of the class described having, in combination, means for working an upper over a last, a binder support, mechanism for actuating it relatively to the over-working means to place the binder tightly about the last, and means for severing the binder from a strand of binder material.
78. A machine of the class described having, in combination, means for working an upper over a last, and means for binding the upper including binder supports on opposite sides of the last mounted and operated independently of the over-working means and relatively movable transversely of the last for placing the binder.
79. A machine of the class described having, in combination, means for working an upper over a last, and means for binding the upper including binder supports relatively movable transversely of the last for placing the binder and movable together and relatively to the wipers lengthwise of the last to tighten the binder.
80. A machine of the class described having, in combination, wipers for lasting an end of a shoe and mechanism independent of the wipers for placing a binder to hold the upper about the end of the shoe and fastening the binder.
81. A machine of the class described having, in combination, means for working an upper over a last, and means for binding the upper including binder supports capable of positioning movements transversely of the last for lasts of different sizes.
82. In a machine of the class described, the combination with a presser movable laterally over a shoe to press the upper material into position to be secured, said presser being constructed and arranged to guide a binder in predetermined position, of automatically operated means for fastening the binder.
83. A machine of the class described having, in combination, means for working an upper over a last, means for binding the upper including binder supports, means for moving said supports transversely of the last to place the binder thereon, and means for automatically limiting the transverse movement according to the size of the last.
84. A machine of the class described having, in combination, means for working an upper over a last, and means for binding the upper including a binder support movable transversely of the shoe in placing the binder, and means for automatically varying said movement according to the size of the shoe.
85. A machine of the class described having, in combination, means for working an upper over a last, means for binding the upper including a binder support movable transversely of the shoe in placing the binder, and yielding means for actuating the support adapted to permit variations in the position to which the support is moved.
86. A machine for working an upper over a last and securing it having, in combination, means for binding the upper including

5 a binder support, yielding means for actuating it to position the binder where it is to be fastened, fastener inserting means, and yielding means for positioning the lat-
5 ter according to the position of the binder.

10 87. A machine for working an upper over a last and securing it having, in combination, means for binding the upper including binder supports, means for yieldingly actu-
10 ating them transversely of the last, and binder fastening mechanisms movable yield-
ingly to find the position of the binder.

15 88. A machine for working an upper over a last and securing it having, in combination, means for binding the upper including binder supports, means for yieldingly actu-
15 ating them transversely of the last to place the binder in predetermined relation to the edges of lasts of different sizes, tacking
20 mechanisms movable from and toward tacking position, and means associated with the supports for determining the extent of movement of the tacking mechanisms.

25 89. A machine for working an upper over a last and securing it having, in combination, means for binding the upper including a binder support, a tacker, and means for actuating relatively to the support the tacker to effect the tightening of the binder
30 and then effect the insertion of a tack in position to fasten the binder.

35 90. A machine for working an upper over a last and securing it with a binder having, in combination, a tacker for fastening the binder, and means controlled by the movement of the tacker for tightening the binder before it is tacked.

40 91. A machine for working an upper over a last and securing it with a binder having, in combination, a tacker for fastening the binder, and means controlled by the movement of the tacker for severing the binder from a strip of binding material.

45 92. A machine for working an upper over a last and securing it with a binder of tape having, in combination, a tape holder and a tacker and having provision for automatically positioning the tacker and tape for the tack to be inserted through the tape.

50 93. A machine for working an upper over a last and securing it having, in combination, means for binding the upper including a binder support, a tacker, and means for

moving the support and the tacker trans-
versely of the shoe for properly positioning them over the shoe bottom.

94. A machine constructed and arranged to work an upper into lasted position and to force a binder into place to hold the lasted upper, having, in combination, means for inserting a tack in position to fasten the binder, and means for cutting the binder from a strand of binder material arranged to operate while the shoe is in binder fastening position.

95. A machine constructed and arranged to work an upper into lasted position and to force a binder into place to hold the lasted upper, having, in combination, de-
vices movable laterally of the last toward
70 and from position to cut the binder from a strand of binding material while the shoe re-
mains in the position occupied by it during the application of the binder.

96. A machine for working an upper over a last and securing it having, in combination, means for binding the upper including binder supports, means for yieldingly actu-
75 ating them transversely of the last to place the binder in predetermined relation to the edges of lasts of different sizes.

97. A shoe making machine having, in combination, means for pulling-over a shoe, means for lasting the forward portion of the shoe, and means for binding the lasted portion of the shoe and arranged for suc-
80 cessive operation while the shoe remains in a single position.

98. A shoe making machine having, in combination, means for pulling-over a shoe, 90 means for lasting the forward portion of the shoe, means for drawing a binder tightly about the lasted portion of the shoe and holding it under tension while it is fastened, and means for fastening the binder all con-
95 structed and arranged for successive and independent operation while the shoe contin-
ues in the machine.

In testimony whereof I have signed my name to this specification in the presence 100 of two subscribing witnesses.

ARTHUR L. RUSSELL.
